HYDRAULIC PUMP

Milford D. Burrows, Stanley Z. Siwek, and Harry Goldberg, Chicago, Ill., assignors to Pioneer Gen-E-Motor Corporation, Chicago, Ill., a corporation of Delaware

Application October 30, 1951, Serial No. 253,875

7 Claims. (Cl. 103—137)

1

This invention relates to an improvement in hydraulic pumps, to be used, for example, in internal combustion engines. It has for one object to provide an oil or other hydraulic pump which is efficient and at the same time compact in structure.

Another object is to provide a pump which can efficiently raise a fluid from one level to another or transfer a fluid from one side to another, through a member integral with, or secured directly to, the rotating hub or rotor of the pump.

Other objects will appear from time to time throughout the specification and claims.

The invention is illustrated more or less diagrammatically in the accompanying drawings wherein:

Figure 1 is a plan view showing some parts in dotted line.

Figure 2 is a section along line 2—2 of Figure 1, with the pump being in the position of Figure 3.

Figure 3 is a section taken on line 3—3 of Figure 2 with parts broken away, showing the pump in a position of its rotation different from that shown in Figure 1.

Figure 4 is a section similar to Figure 3, showing the pump in a third rotational position.

Figure 5 is a side elevation of the outlet portion of my invention.

Figure 6 is a plan view of a plate which partially seals the housing of the pump.

1 designates generally a vane-carrying rotor head or rotor hub which is secured to and preferably integrally formed with a hollow rotating shaft 2, as shown in Figures 2 and 5; the parts 1 and 2 forming together a rotor. The hub 1 is conveniently formed of two sections 3 and 4, there being between such two sections a channel 5, the depth of which is equal to the thickness of the hub at its circumference, with the result that the outer edges of vanes 6 and 7 extend the full distance from the top to the bottom of the hub 1, as shown most clearly in Figure 2. The purpose of the channel 5 is two-fold: to enable the vanes to shift as required, and to provide a space for the passage of oil through the hub. The hub 1 is characterized by an orifice 8 passing through the hub along or substantially along its axis of rotation. Such orifice consists of a portion of the channel 5, and also of the grooves 9 provided one in each hub section 3 and 4 to increase the area available for the passage of the fluid.

It would probably be equally practicable to use instead of the form disclosed and discussed so far in the specification, a form of rotor in which the portion carrying the vanes was of the same diameter as the rest of the rotor. I find the form disclosed herein more convenient, however, because that portion of the rotor head 1 which extends outwardly beyond the rotor shaft

2

and fits snugly against opposing surfaces of the housing 10 provides a very convenient and effective means of preventing leakage of the fluid.

The hub 1 and vanes 6 and 7 are housed in a housing 10, which may consist of a suitably-dimensioned recess in part of an engine block. Such a housing might also comprise a pre-assembled unit or capsule, secured adjacent or fitted into an opening in an engine block. The housing has a fluid inlet, as at 11, to accommodate fluid from an intake passage 12. It has a tubular opening at 13 formed to receive the rotor shaft 2, which, as is hereinafter more fully set forth, serves both as a member to rotate the rotor hub 1 and as a fluid outlet tube; and has an enlarged hollow portion 13(a) for the accommodation of the rotor head 1. Thus an overall pump chamber is defined by the hollow portions or openings 13 and 13(a).

The shaft 2 enters the housing 10 at such a point, as illustrated in Figure 2, and the hub 1 is so positioned in the housing, as shown in Figures 1, 3 and 4, that the hub 1 rotates about a center which is eccentric relative to the circumferential inner wall of the housing 10. The lower surface 14 and upper surface 15 of the hub 1 fit snugly against the opposing flat surfaces of the housing 10. A spring 16, shown most clearly in Figure 2, positioned between the two vanes 6 and 7, urges the vanes outwardly at all times. As a result, the upper, lower, and outer edges of each vane fit snugly at all times against the top and bottom surfaces and sides, respectively, of the interior of the housing.

Fluid intake passage 12 introduces oil or other fluid into the housing 10 at a point 17 where the distance between the circumference of the hub 1 and the inner wall of the housing is relatively great, as shown in Figures 1, 3 and 4. The purpose of such positioning of the fluid inlet will become apparent later in the specification.

The housing 10 is partially sealed by a plate 18, shown in plan view in Figure 6 and in partial plan view in Figures 3 and 4, this plate constituting an end wall closure. This plate possesses apertures 19 for screws, a hole, designated as 8a, which is positioned directly below, and thus constitutes a part of, the hub orifice 8; a fluid escape port 20; and an inlet 21 through which fluid intake 12 passes as it flows to the housing. When the plate 18 is in position against the housing, the fluid escape port 20 is positioned at a point where the distance between the circumference of the hub 1 and the inner wall of the housing is relatively small, as shown in Figures 1, 2, 3 and 4, to afford an outlet for oil which is introduced through the inlet passage 12 and subsequently put under pressure.

The fluid escape port 20 and the opening 8a must be made to communicate, and this could

easily be done by providing the plate 18 with an integral passage, or with a tube connecting these openings and providing a return for the fluid. We prefer, however, a second plate 22, shown in section in Figure 2 and in plan view in Figure 1, fitting snugly against plate 18 as shown in Figure 2. This plate has a hole 23 through which the fluid inlet passage 12 passes, but no other apertures through which oil may pass, only apertures, not shown, to accommodate the screws 24 which secure both plates snugly against each other and against the housing. The plate 22, however, provides a passage for the fluid under pressure, by means of an indented portion or channel 25. As shown in Figures 1 and 2, channel 25 extends from a point under fluid escape port 20 to a point under the center of the hub 1. This channel 25 thus communicates with the channel 5 and orifice 8 of the hub 1 through the opening 8a in plate 18, which opening comprises an outlet passage from channel 25 for the oil under pressure. A continuous passage for this oil, after it passes through plate 18 and hub orifice 8a, is formed by the hollow rotating shaft 2, its hollow center 26 ending in an oil outlet 27. A constriction 28 in the hollow center 26 puts the oil under additional pressure. As shown in Figures 2 and 5, a gear 29, by means of which the pump is driven, is secured in place by a washer 30 and a nut 31 which is in threaded engagement with the outer end of the shaft 2.

In operation, the rotation of the hub 1 and of the vanes 6 and 7 sucks oil into the housing 13 through the inlet passage 12. The various positions of the vanes during the rotation of the hub 1 are illustrated in Figures 1, 3 and 4. From these figures it will be seen that the vanes 6 and 7 are at all times pressed outwardly by the spring 16 in such a way that the outer edges of the vanes are in constant fluid-tight pressure against the inner walls of the housing. Also it will be seen that as the eccentric mounting of the hub causes the vanes and spring to shift in the channel 5, there is always a passage through the hub since the spring keeps the two vanes apart in the channel. The location of the space between the vanes 6 and 7 varies little as the hub rotates, and the orifice 8 is never completely blocked. As the hub, and with it the vanes, rotate, oil picked up through the inlet at 17 is put under increasing pressure as the vane 6 continues its rotation and thus pushes the oil which is ahead of it toward the constriction which is effected by the eccentric position of the hub 1, as a result of which the hub 1 is much closer to the inner wall of the housing at the point X than at the inlet point 17 where the oil is picked up. As a result of this pressure, which increases as the vane 6 rotates toward the constriction, the oil escapes readily through fluid escape port 20. From this point it travels through channel 25 in the plate 22, thence through the opening 8a in plate 18, and through the orifice 8 and channel 5 of the hub 1. From the orifice 8 it passes on into the hollow center 26 of the rotating shaft 2. It will be noted that although the positions of the two vanes vary during the rotation of the hub, insofar as their respective extensions from the hub are concerned, nevertheless, because of the spring 16, the actual position of this space changes very little. A space is always left between the two inner ends of the said vanes, and is further provided by the enlargements 9. The orifice 8 is thus at all times at least partially open for the passage therethrough of oil.

The oil passing upwardly through the hollow center 26 comes under increased pressure at the constriction 28, and leaves the rotating shaft 2 at 27 under such increased pressure.

It will be realized that whereas we have described and claimed a practical and operative device, nevertheless many changes may be made in size, shape, number and disposition of parts without departing from the spirit of our invention. We therefore wish our descriptions and drawings to be taken as in a broad sense illustrative or diagrammatic rather than as limiting us to our precise showing herein. For example, the pump herein described and claimed, although advantageously useable as a lubricating pump for internal combustion engines, may be applied to other uses or situations where a lubricant or other liquid is to be moved or delivered.

We claim:

1. In a hydraulic pump, a housing portion defining a pump chamber having a fluid inlet, a rotor having a portion positioned in said chamber and a longitudinal delivery passage extending axially through the rotor to a delivery point remote from the chamber which constitutes a fluid outlet, the rotor being rotatable about an axis eccentric to the axis of the chamber and having a lateral channel in communication with the delivery passage, vanes slidable in the lateral channel, means for normally urging each of the vanes outwardly against the inner surface of the chamber, the space between the vanes defining an arcuate fluid passage with the housing, and a removable end wall closure for the chamber having a channel in communication with the arcuate fluid passage and in communication with the delivery passage so that fluid flowing through the arcuate fluid passage from the fluid inlet flows through the channel in the end wall closure, through the delivery passage, to the delivery point remote from the chamber.

2. The structure of claim 1 wherein the chamber has a circumferential wall.

3. The structure of claim 1 wherein the vanes in the lateral channel are diametrically opposed.

4. The structure of claim 1 wherein the portion of the rotor positioned in the chamber is greater in diameter than the remainder of the rotor.

5. The structure of claim 1 wherein the fluid inlet to the chamber is at a point where the spacing between the rotor and the chamber is relatively large.

6. The structure of claim 1 wherein at least two vanes are disposed in the lateral channel in the rotor.

7. The structure of claim 1 wherein the channel in the removable end wall closure is laterally disposed with respect to the rotor.
